UNITED STATES PATENT OFFICE.

FREDERICK A. KOETITZ, OF SAN FRANCISCO, CALIFORNIA.

FITTINGS FOR CONCRETE CASINGS.

No. 825,604.

Specification of Letters Patent.

Patented July 10, 1906.

Application filed March 8, 1906. Serial No. 304,964.

To all whom it may concern:

Be it known that I, FREDERICK A. KOETITZ, a citizen of the United States, residing in the city and county of San Francisco and State of California, have invented new and useful Improvements in Fittings for Concrete Casings, of which the following is a specification.

My invention relates to fittings which are applicable especially to concrete casings for piles.

It consists in the combination of parts and in details of construction which will be more fully explained by reference to the accompanying drawings, in which—

15 Figure 1 shows an application of my improved casing. Figs. 2 and 3 are detail views of the cap. Figs. 4 and 5 are views of the splice-ring. Figs. 6 and 7 are views of the shoe.

20 For the purpose of providing supports for wharves and like structures piles are driven, and these piles may be inclosed in concrete casings, as shown in Patent No. 788,410, issued to me April 25, 1905.

25 My present invention is designed to connect several sections of concrete casings together, to maintain them in line, to provide guides for the piles in order to maintain them substantially central within the casing, 30 and to reinforce the concrete fillings and form anchors for superstructure and for other purposes of like nature.

35 As shown in the drawings, A is a hollow concrete casing of cylindrical or other form and of any suitable or desired size. This casing is of sufficient diameter to receive the pile or other structure which may be used in conjunction with it. In the present drawings I have illustrated my invention as especially applied to the inclosure and protection 40 of piles; but it will be manifest that it may be equally well employed on other and similar structures requiring protection.

45 As herein shown, the casing A is made in lengths or sections, and at the junction of these sections I have shown the interior fittings 2 covering the junction of two casing-sections. I have shown these fittings as in the form of sleeves having an exterior diameter 50 which will fit within the casing, and annular flanges 3 project outwardly and enter correspondingly-shaped grooves formed by beveling the meeting ends of the casing-sections. Projecting inwardly from these 55 sleeves are lugs 4 at stated and substantially equal intervals around the inner periphery,

these lugs being adapted to receive vertically-disposed tie-rods 5, which extend down through the splice-fittings and also through a cap 6 at the upper end of the casing and a shoe 7 at the lower end and suitably secured. The cap 6 has a shape similar to that of the casing, which in the present case is circular, and has a sleeve or flange 6^a extending downwardly within the casing, which it substantially fits, and the inwardly-projecting portion of the cap has holes or perforations corresponding with and in line with the rods 5, so that the latter may extend up through the cap and to a distance sufficient to connect with and form anchors for the superstructure of whatever nature. The inwardly-projecting overhanging portion of the cap may have angular brackets 6^b extending downward at intervals and upon each side of the rods 5, where they pass through these flanges, forming the brackets supporting the inwardly-overhanging portion of the cap and sustaining it against the pressure of locking-nuts or the weight of the superstructure which may rest thereon.

The shoe for the casing is formed with the horizontal portion 7 forming a shelf or support for the bottom section of the casing, having an upwardly-extending annular flange 7^a 85 with bracing-brackets similar to those of the cap-piece to sustain the inwardly-projecting portion of the bottom of the shoe. The part 7^c of the shoe is made conical or tapering to prevent too much soil from entering the casing, and the inner edge of the part 7^c forms a guide against the pile which has been previously driven. The casing may thus be united and sunk upon the bottom, or if it is soft and it is desirable it may be sunk into the soft 90 material, as far as may be desired, and the sections of the casing are firmly secured together by the vertical tie-rods 5 to form a 95 unitary structure. The pile is first driven in the usual manner or old piles for repair-work 100 are cut off at about water-level, and the inner periphery of the shoe serves as a guide against the pile and maintains the casing at the proper distance from the pile to allow a body of concrete to be filled into the annular space 105 between the pile and casing, thus making a solid structure.

The lugs 4 of the spliced sleeves form guides to maintain the tie-rods properly spaced within the structure, and these rods 110 remain in place and act as a reinforcement of the concrete filling.

Having thus described my invention, what I claim, and desire to secure by Letters Patent, is—

1. Hollow concrete casings formed in sections capable of being sunk in the earth at the bottom, and over piles already in place, sleeves forming splices at the junction of the sections, tie-rods extending longitudinally through the casings, said sleeves having ¹⁰ perforated flanges through which the rods pass, and concrete filling within the casings.
2. An independent hollow concrete casing consisting of sections, sleeves located within the sections at their junction, a cap-piece and ¹⁵ shoe and tie-rods extending through the cap-piece and shoe, and a pile located within the casing and shoe.
3. An independent hollow concrete casing composed of sections axially in line, interior ²⁰ sleeves covering the junction of the sections and having annular flanges projecting into channels formed in the sections at their junction, interior perforated lugs, a cap-piece and a shoe having flanges extending inwardly and ²⁵ perforated in line with the lugs of the junction-sleeves, and tie-rods extending through said openings.
4. An independent hollow concrete casing formed in sections having interior grooves or ³⁰ channels at their meeting ends, sleeves fitting within the casings and having flanges projecting into the grooves thereof, spaced guide-lugs extending inwardly from the sleeves, a cap-piece resting upon the top of the casing ³⁵ and projecting inwardly therefrom, and a flange fitting the interior of the casing, vertical openings in the interior portion of the

cap in line with the lugs of the junction-sleeves, a shoe upon which the bottom of the casing rests, said shoe extending inwardly ⁴⁰ and having openings corresponding with those of the cap, spaced tie-rods extending through the cap, the shoe and the spacer-lugs, a pile around which the inner periphery of the shoe of the casing is fitted, and a filling ⁴⁵ of concrete between and above the pile and the inner walls of the casing.

5. A hollow concrete casing composed of independent lengths axially in line and having interior grooves or channels formed at ⁵⁰ the junction of the sections, sleeves fitting the interior of the casing and having outwardly-projecting flanges fitting the grooves of the sections and inwardly-projecting lugs at intervals, a cap-piece and a shoe against ⁵⁵ the outer portion of which the top and bottom of the casing abut, said cap-piece and shoe extending beyond the inner wall of the casing and having sleeves extending into the ⁶⁰ casing, brackets spaced to coincide with the lugs of the joint sleeves and having openings made between them, tie-rods extending through said openings and the sleeve-lugs and projecting inwardly to form anchors for the superstructure, a driven pile within the ⁶⁵ casing, and a subsequent filling of concrete between and above the pile and the casing.

In testimony whereof I have hereunto set my hand in presence of two subscribing witnesses.

FREDERICK A. KOETITZ.
